UNITED STATES PATENT OFFICE.

MORRIS WEINER AND WILLIAM LOEB, OF NEW YORK, N. Y.

DESIGN FOR A WATCH-COVER OR SIMILAR ARTICLE.

52,835.

Specification for Design.

Patented Dec. 31, 1918.

Application filed September 19, 1918. Serial No. 254,878. Term of patent 7 years.

To all whom it may concern:

Be it known that we, MORRIS WEINER, a citizen of Russia, and resident of the city of New York, county of Bronx, and State of New York, and WILLIAM LOEB, a citizen of the United States, and resident of the city, county, and State of New York, have invented a new, original, and ornamental Design for a Watch-Cover or Similar Article, of which the following is a specification, reference being had to the accompanying drawings, forming part thereof.

In the drawings, Figure 1 is a plan view of a watch or locket cover, the opening 1 in the center embodying our new design and the outline 2 being shown simple in form.

Fig. 2 is a section of Fig. 1 on line A—A thereof.

What we claim is:

The ornamental design for a watch cover or similar article, as shown.

MORRIS WEINER.
WILLIAM LOEB.
